UNITED STATES PATENT OFFICE.

JOHN H. MERTZ AND BENJAMIN F. DAVIS, OF CHICAGO, ILLINOIS.

DESIGN FOR A BADGE.

SPECIFICATION forming part of Design No. 33,155, dated September 4, 1900.

Application filed July 5, 1900. Serial No. 22,632. Term of patent 3½ years.

To all whom it may concern:

Be it known that we, JOHN H. MERTZ and BENJAMIN F. DAVIS, citizens of the United States, residing at Chicago, in the county of Cook and State of Illinois, have invented and produced a new and original Design for Badges, of which the following is a specification, reference being had to the accompanying drawing, forming a part thereof, in which

5 the figure is a face view of a badge showing our new design.

The leading feature of our design consists of a badge having the shape and ornamentation shown in the accompanying drawing.

15 The badge, made from any suitable material, is circular in shape and bears thereon the following configuration or picture, which is also circular in shape to conform to that of the badge. In the immediate foreground is represented a field of grain in shocks and in the middle foreground a team and wagon loaded with sheaves, beyond which are shown a farm-house and other buildings, with a background of trees and foliage. Upon the right

20

in the foreground appears a body of water having mills, factories, and smoking chimneys upon its banks. In the sky of the background is represented a sunburst, with light-shafts radiating therefrom, while a portrait of President McKinley is shown upon the face of the sun. Protruding from beneath the picture, as shown at *a a*, are groups of stars upon a contrasting field, and upon the sides, as shown at *b b*, are contrasting stripes.

Having thus described our invention, what we claim as new, and desire to secure by Letters Patent, is—

The design for a badge as herein shown and described.

In testimony whereof we have signed this specification in the presence of two subscribing witnesses.

JOHN H. MERTZ.
BENJAMIN F. DAVIS.
